[57] CLAIM

The ornamental design for a portable patio deli appliance, as shown and described.

DESCRIPTION

FIG. 1 is a perspective view of a portable patio deli appliance showing my new design;

FIG. 2 is a front elevational view thereof;

FIG. 3 is a front elevational view thereof showing a refrigeration compartment door in an open position and the interior of the refrigeration compartment;

FIG. 4 is a rear elevational view thereof;

FIG. 5 is a right side elevational view thereof;

FIG. 6 is a left side elevational view thereof;

FIG. 7 is a left side elevational view thereof showing a dry storage compartment door in an open position and the interior of the dry storage;

FIG. 8 is a top plan view thereof; and,

FIG. 9 is a bottom plan view thereof.

A portion of the cord in FIGS. 1, 4, 5, 6 and 7 is shown broken away for convenience of illustration.
